UNITED STATES PATENT OFFICE

101,437

DESIGN FOR A COMBINED CIGARETTE PACKAGE HOLDER AND ASHTRAY

Arthur T. Ball, Wallingford, Conn.

Application August 22, 1936, Serial No. 64,516

Term of patent 7 years

To all whom it may concern:

Be it known that I, Arthur T. Ball, a citizen of the United States, residing at Wallingford, in the county of New Haven and State of Connecticut, have invented a new, original, and ornamental Design for a Combined Cigarette Package Holder and Ash Tray, of which the following is a specification, reference being had to the accompanying drawing, forming part thereof.

Fig. 1 is a perspective front view of a combined cigarette package holder and ash tray in the closed position showing my new design; and

Fig. 2 is a perspective rear view of the same in the open position.

I claim:

The ornamental design for a combined cigarette package holder and ash tray substantially as shown.

ARTHUR T. BALL.
